E. H. SOMMER

CHILD CARRIER

Filed April 9, 1925

Inventor
Ella H. Sommer

By Bair, Freeman & Latta, Atty

UNITED STATES PATENT OFFICE.

ELLA H. SOMMER, OF SIOUX CITY, IOWA.

CHILD CARRIER.

Application filed April 9, 1925. Serial No. 21,839.

To all whom it may concern:

Be it known that I, ELLA H. SOMMER, a citizen of the United States, and a resident of Sioux City, in the county of Woodbury and 5 State of Iowa, have invented certain new and useful Improvements in Child Carriers, of which the following is a specification.

My invention relates to a small seat in which a child may be carried suspended 10 from the hands of two persons, suspended from a stationary object, or within an automobile vehicle.

An object of my invention is to provide such a seat which is of simple, durable and 15 inexpensive construction, which is of very light weight, and collapsible to a small package.

Another object of my invention is to provide a seat which is quickly convertible from 20 a carrying seat to a hammock or a seat adapted to be suspended from a stationary object.

Another object of my invention is to provide a seat adapted to snugly receive a 25 child, secure it in position and to adapt it self to fit the body of the child so as to induce comfort.

More particularly, my invention is embodied in a seat comprising a hinged, collapsible seat member, a back and sides formed 30 of a single sheet of fabric secured to said seat member on three sides thereof, a pair of handles secured in the fabric of the sides, to which may be attached suspending straps 35 and fastening devices secured to the back and bottom member, or to which may be secured extensions for forming a hammock.

With these and other objects in view, my invention consists in the construction, arrangement and combination of the various 40 parts of my device, whereby the objects contemplated are attained, as hereinafter more fully set forth, pointed out in my claim, and illustrated in the accompanying drawings, 45 in which:

Fig. 1 is a perspective view of the seat as carried by the hands.

Fig. 2 is a sectional view taken on the line 2—2 of Fig. 1.

50 Fig. 3 illustrates the seat collapsed.

Fig. 4 shows the seat with suspending straps attached, suspended from a stationary object.

Fig. 5 shows the seat converted into a 55 hammock, and

Fig. 6 is an inverted plan of a portion of the seat member with the hammock extensions attached.

I have used the reference character 10 to indicate a section of thin board which forms 60 a frame for a portion of the seat member. A similar board, 11, having one straight side and the other side curved in elliptical shape, as shown in Fig. 1, forms a base for the remainder of the seat.

65 A cloth envelope formed of an upper and lower sheet, 12 and 13, respectively, covers the boards, 10 and 11, and is raised by means of padding, 14, to form cushions. The cloth sheets, 12 and 13, are sewed together, 70 as at 15, to form a hinge between the two sections of the seat. The sheets are joined at their edges, as at 16 in Fig. 1, by sewing.

The back, 17, and sides, 18, of the seat are 75 formed of a single sheet of material, sewed to the edges of the envelope, their upper edges being substantially parallel with the edge of the seat, as shown in Fig. 2.

The sides, 18, are provided with loops, 19 and 20, between which the fabric of the sides 80 is cut away as at 21.

Wooden handles, 22, are secured in the loops, 20, by brads, 23, or other means. The handles, 22, are formed of short, straight sections of round, wooden rods in order to 85 allow ready attachment of the hinged straps, which will later be described.

To the side members, 18, near the rear portions thereof, are secured straps, 24 and 25, the strap, 24, being provided with a 90 buckle, 26, to receive the end of the strap, 25.

When a child is supported in the seat the straps may be secured around its body to effectively prevent it falling from the chair.

The seat may be carried between two persons while walking by means of the handles, 22, which are grasped by the hands of the persons, and may be deposited upon any flat surface with the child retained in 100 place.

I provide a pair of straps, 27, which have at their lower ends co-acting snap devices, 28 and 29, by means of which the ends of the straps may be looped around the handles, 22, 105 in the upper ends of the straps are sewed rings, 30, which may be hooked over screw hooks, 31, secured in an object such as a limb, 32, of a tree, and the seat thereby suspended in a stationary, swing-like posi- 110

tion. When so suspended the seat may be used as a child's swing.

In Figs. 5 and 6 I have illustrated the hammock attachment for the seat. The 5 triangular strip of fabric, 33, is provided at one end with a ring, 34, and at the other with armored openings, 35, designed to receive fasteners, 36, secured in the bottom and back of the seat, respectively, as shown 10 in Fig. 2. Two of the extensions, 33, are provided, one to be fastened to the bottom of the seat and the other to the back. The fastening members, 36, on the back are arranged in a row of several fasteners extending 15 from side to side, and when the seat is suspended from the extensions the rear extension, 33, will assume a dished shape conforming to the rounded contour of the seat back.

20 The straps, 24 and 25, may be utilized in this case to maintain the child in the hammock and the handles, 22, allowed to depend freely as shown. The rings, 34, may be supported from suitable hooks provided for 25 hanging the hammock, or may be strapped to the back seat and front seat, respectively, of a vehicle so as to suspend the child over the rear seat thereof.

It will thus be seen that the child's seat 30 is readily convertible from a carrying seat to a swing, or to a hammock, and may be

folded when not in use to a very small package, as shown in Fig. 3.

The use of handles maintains the fullness of the contour in the upper part of the seat 35 and prevents the sides and back drawing together when the weight of the child is placed upon the seat. The strain is thus transmitted from the seat to the handles, as indicated by the lines, 37, and the seat member will be retained in level position in spite of the hinged construction thereof.

Some changes may be made in the construction and arrangement of the parts of my invention without departing from the 40 real spirit and purpose of my invention, and it is my intention to cover by my claim any modified forms of structure or use of mechanical equivalents which may be reasonably included within its scope. 45

I claim as my invention:

In a child's seat, a seat member, a back and sides formed of a sheet of fabric secured to the edge of the seat member on three sides thereof, handles secured to the upper edges of the sides, and fastening devices on the back and on the bottom member, to which may be secured hammock extensions. 50

Signed at Sioux City, in the county of Woodbury and State of Iowa, this 25th day of March, 1925.

ELLA H. SOMMER.
